UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

REGENERATIVE HEATING FURNACE.

Application filed April 22, 1922. Serial No. 555,941.

This invention comprehends improvements in regenerative heating apparatus generally and particularly to apparatus that is especially adapted for distilling carbonaceous materials; the invention has for an object the provision of a construction that is highly efficient in operation and which will produce high grade coke, when employed for distilling coal, and effect a substantially complete by-product recovery by a distilling operation conducted with great conservation of heat.

Important characteristics of the invention are: the provision of a system of combustion in the flame or combustion flues of the heating walls of the distilling chambers, by which system flame or combustion is maintained concurrently in all of the flues of each heating wall, with periodic reversal in direction of flow of the heating gases and the attainment of efficient combustion and heating effects in each direction of flow of the heating gases; the combination of this improved system of combustion with a complete reversible regenerative system for conserving the heat from the combustion flues and imparting such heat to the medium fed into the flues, the regenerative system being constructed and arranged with respect to the flues and connected therewith in such manner as to attain great efficiency in heat conservation and equality in distribution of the heating effect in the several distilling chambers of the battery; a ready adaptability for operation with an extraneously derived gas such as producer gas or blast furnace gas, for fuel, with a resulting conservation of the entire product of the relatively richer gas of distillation evolved from the distillation of the material, such as coal, in the distilling chambers; and, as a further characteristic combinable with the above mentioned improvements, the provision of a structure having gas-flow passageways leading directly between the regenerators and the flues and arranged so as to promote maximum simplicity in construction of the flow areas connecting the regenerators with the flues, with the concurrent attainment of a structure of great strength for withstanding expanding and contractive forces, and in which the regenerative regions may expand or contract independently of the flue and port areas.

In addition to the general objects recited above, the invention has for further objects

such other improvements and advantages in construction and operation as are found to obtain in the structures and devices herein-after described or claimed.

In the accompanying drawings forming a part of this specification and showing, for purposes of exemplification, a preferred form and manner in which the invention may be embodied and practiced, but without limiting the claimed invention specifically to such illustrative instance or instances:

Fig. 1 is a composite vertical sectional and elevational view of a vertical retort construction embodying features above specified and constructed in accordance with the improvements of the present invention, the view being taken in the several vertical planes indicated by the lines A—A, B—B and C—C of Fig. 2;

Fig. 2 is a composite vertical sectional elevation of the retort construction taken in planes indicated by the lines D—D and E—E of Fig. 1;

Fig. 3 is a composite horizontal sectional and plan view, the sectional portions of the figure being taken in the different horizontal planes indicated by the lines F—F and G—G of Fig. 5;

Fig. 4 is a horizontal sectional elevation taken in a plane indicated by the line H—H of Fig. 5; and

Fig. 5 is a vertical section taken in a plane indicated by the line K—K of Fig. 3.

The same characters of reference designate the same parts in each of the several views of the drawings.

In its present embodiment, the invention is incorporated in a vertical retort construction for producing metallurgical coke and one that is especially designed for the employment of an extraneously derived gas, such as producer gas, for fuel. For convenience, the present description will be confined to this embodiment of the invention; features of construction and operation are, however, capable of other valuable applications, for example, to apparatus generally useful in the heat treatment of materials or to constructions employing as fuel the distillate gas derived from the distilling chambers, or to constructions embodying the combination principle exemplified in my co-pending application for Letters Patent of the United States for vertical retort battery, filed February 4, 1921, Serial No. 442,357; 110

consequently the invention is not confined in its scope to the specific use and embodiment herein described as an illustrative example.

Referring to the drawings: there are illustrated views of a vertical retort battery of the by-product type, as hereinbefore mentioned. The vertical retort battery embodies in its construction two series of distilling chambers, such as the series 11 and 12 of vertically elongated retorts or coking chambers, the retorts of each series being contiguous to intermediate heating walls arranged in the two series 13 and 14 corresponding to the respective series of retorts 11, 12. The heating walls and the retort chambers extend to a great height as compared with their respective widths and the other crosswise dimensions of the retort battery, and the two series of retorts with their corresponding intermediate heating walls are, according to the present embodiment of the invention, respectively arranged and extend along the opposite sides of the central longitudinal vertical plane of the battery assembly so as to provide an enclosed space intermediate the opposite sides of the battery for the regenerators, as will hereinafter appear. The heating walls 13, 14 form the side walls of the respective retorts 11, 12, as shown, and the outer ends of the respective retorts as well as the heating walls are reinforced by side refractory walls designated generally by the reference character 15. Between the oppositely facing inner ends of the two series of retorts 11, 12 and their corresponding series of heating walls 13, 14 is located a mediate chamber and wall structure 16 employed for the regenerators and other parts hereinafter described.

As shown in Figs. 3 and 4, the retorts of the two series 11 and 12 may be respectively grouped into pairs K and L and the heating walls of the series 13 and 14 may be arranged in groups M and N, corresponding to the pairs of retorts K and L of the series 11 and 12. This arrangement permits the location of a relatively thick transverse wall 17 between each pair of retorts and its corresponding group of heating walls, with the result that ample space is provided for handling of the material carbonized in the retorts of the battery.

The coal to be coked is contained in coal hoppers 18 and 19 corresponding to the series 11, 12 of retorts and supported by the superstructure 20 of the retort battery. These coal hoppers discharge into coal chutes 21 and 22, the lower ends of each communicate with charging holes 23 and 24 in the upper ends of the retorts of the series 11, 12. The discharge of coal from the several hoppers may be controlled by the manually-operated combined gate and regulating valves 25 individual to the respective chutes 21, 22 and interposed between said chutes

and the hoppers 18, 19 above them. The fresh coke is discharged through discharge openings 26 at the bottom of the retorts 11, 12. In order to facilitate discharge of the coke from said retorts, the side walls of the latter diverge toward the bottom, as shown more particularly in Fig. 1. Because of the great height of the retorts as compared with their width and crosswise dimension, the retort battery is preferably employed as a continuous vertical retort. When so employed, a continuous feed of material is maintained through the retorts 11 and 12, with a continuous discharge of the finished coke from the bottoms of said retorts into discharge chutes 27 individual to the retorts 11, 12. In the upper portion of the chutes 27, the coke is quenched by water supplied from the pipe connections 29 individual to the several chutes 27, the steam produced from the quenching operation being allowed to pass upwardly through the open discharge outlets 26 at the bottoms of the retorts 11, 12 and through the mass of forming coke in said retorts. The introduction of this steam into the retorts may be supplemented by steam pipes 29^a and permits the continuous maintenance of a water gas reaction in the forming coke, with the result that the gas yield from the retorts 11, 12 is improved. In discharging through the chutes 27 the coke is guided by pivoted aprons 30 into the path of rotary discharges 31 which insures substantial continuous movement of the finished coke through the chutes 27. From the bottoms of the chutes 27 the coke may be discharged at will through manually-controlled gates 32 on to inclined coke wharves 33, there being an inclined wharf corresponding to each series of retorts 11 and 12. The wharves 33 converge downwardly, as shown in Fig. 2, toward an intermediate coke conveyer 34 and the discharge from the wharves 33 on to the coke conveyer 34 may be controlled by the individual pivoted gates 35 operated by slides 36.

The heat for coking the charges of coal in the several retorts 11, 12 is derived from the heating walls 13, 14 corresponding to said retorts. Each heating wall 13, 14 is constituted of a plurality of vertical combustion flues 37 that are operatively disposed into single groups in their respective heating walls. That is to say, all of the heating flues of each heating wall operate concurrently for flow in the same direction; in fact the flow is in the same direction during a reversal period throughout the entire system of each unit of flues of the battery, as will hereinafter appear.

The regenerators 38 are incorporated in the above mentioned internal structure 16. As shown in Fig. 4, the several regenerators of the battery are structurally disposed into groups T, the several groups being separated

by the intermediate crosswise walls 17 and the regenerators of each group functioning only with respect to the flues 13, 14 that are between the same transverse walls as those 5 which bound the corresponding group of regenerators. With this construction, the entire battery is subdivided by the walls 17 into completely independent operating units, any one unit of which may be operated entirely 10 independently of and without regard to the other operating units with the result that individualized control is permitted in the several groups of distilling chambers of the entire battery. Operating units of the battery 15 may be shut off or operated with different materials or in an entirely different manner from the other units of the battery without any effect on such other units, each unit being in fact a complete small heating 20 battery in itself. Operatively, each group T of regenerators is disposed into two sub-groups R and S, the sub-group R comprising the two centrally located regenerators of the entire group and the two regenerators 25 at the extreme ends thereof and the sub-group S comprising the two pairs of regenerators which are disposed on the opposite sides of the center pair of regenerators of the sub-group R. When the several regenerators 30 constituting the group R are operating for inflow, that is to say, for delivering preheated gaseous media to the flues of the heating walls, the several regenerators of the other group S are operating for outflow to extract heat from the flue gases discharged into the regenerators from the flues. On reversal of the battery, at the end of an operating period determined by practice, the inflow regenerators become outflow regenerators 35 and the outflow regenerators become inflow regenerators.

Each regenerator 38 is preferably a high narrow upright chamber containing open brickwork, commonly called checkerwork 40 and indicated at 40 with a sole channel 41 underneath such checkerwork, the channels 41 forming the soles of such chambers and opening up into the checkerwork. The several regenerators are heated, by the hot combustion products that are exhausted from the flame or combustion flues hereinbefore mentioned and then, on reversal, impart such heat to the medium that they feed into these flame flues.

In the operation of the battery, according 45 to the present embodiment of the invention which employs an extraneously derived gas, such as producer gas, for fuel, the several regenerators constituting the group R, when in inflow operation, deliver air and fuel gas to the flame flues during the period when the latter are operating for downflow combustion; these regenerators R receive the exhaust gases from the flame flues after reversal, that is to say, during the period when 50 the flame flues are operating for upflow combustion. On the other hand, the several regenerators constituting the group S operate for inflow of air and fuel gas to deliver the same to the flues when the latter are operating for upflow combustion, and the said regenerators S operate for outflow to receive the exhaust gases from the flues during the period when the latter are operating for downflow combustion. This method of operation requires the regenerators R to be connected with the upper ends of the flame flues 37 and the regenerators S to be connected with the lower ends of said flame flues. The several regenerators of each group R and S are constituted of air regenerators A and gas regenerators B, when operating for inflow, and all the regenerators of each group are constituted of waste gas regenerators W when operating for outflow. 55 However, the several regenerators R operate for inflow while at the same time the several regenerators S operate for outflow and, on reversal of the flow through the flame flues, the several regenerators S are switched to the inflow function while concurrently the other regenerators R are switched to the outflow function.

As shown, the regenerators A of the sub-group R communicate at their upper ends 60 by ports 41 with horizontal feed channels 42 disposed at the opposite ends of their respective regenerators and leading over the tops of the flues of the heating walls 13 and 14, whereby each flue of each heating wall on both sides of the battery may have connection with an air supplying regenerator through the top of the flue, whenever the direction of combustion is downwardly through the flue. The horizontal channels 65 42 communicate with the individual flues by ports 43. As shown in Fig. 3 the horizontal feed channels 42 which are connected to the end regenerator A of the sub-group R lead only to single heating walls on 70 opposite sides of the longitudinal center of the battery, whereas the horizontal feed channels 42 companion to the centrally located regenerator A respectively lead, on opposite sides of the battery, to a pair of adjacent heating walls. The regenerators P of the sub-group are also communicably connected by ports 44 with horizontal channels 75 45 leading from the opposite ends of said regenerators P to and extending over the tops of the flues of the heating walls 13 and 14 and communicably connected with the individual flues thereof by ports 46. The end regenerator P is communicably connected by such channels 45 with only single heating walls on the opposite sides of the longitudinal center of the battery, but the centrally located regenerator P is communicably connected with pairs of adjacent heating walls on both sides of the aforesaid longi- 80 85 90 95 100 105 110 115 120 125 130

tudinal center. With this construction, the regenerators P and A of the sub-group R have flow connections with the upper ends of all the individual flues corresponding to 5 each main group T of regenerators.

The several regenerators A of the sub-group S lead at their upper ends into horizontal feed channels 51, the latter communicating at their opposite ends by ports 52 with vertical feed channels 53 disposed on opposite sides of the longitudinal center of the battery. These vertical feed channels 53 communicate at their lower ends with horizontal channels 54 extending beneath the 15 groups of flues of both series 13, 14 of heating walls and communicably connected with the individual flues by ports 55. The channels 54 leading from one of the regenerators A of the sub-group S communicate with only 20 single heating walls on both sides of the battery, whereas the channels 54 leading from the other regenerator A of the sub-group S communicate with pairs of adjacent heating walls on the opposite sides of the 25 battery. In the same manner, the regenerators P of the sub-group S lead at their upper ends into horizontal channels 56 and the latter are communicably connected at their opposite ends by ports 57 with vertical feed 30 channels 58 disposed at opposite sides of the battery. The vertical feed channels 58 similarly communicate at their lower ends with horizontal channels 59, the latter extending beneath the flues of both series 13, 14 of the 35 heating walls and being communicably connected therewith by means of ports 60. The channels 59 leading from one of the regenerators P of the sub-group S communicate with only single heating walls on the opposite 40 sides of the battery, whereas the channels leading from the other regenerator P of the sub-group S communicate with pairs of heating walls on the opposite sides of the battery. With the above construction, as 45 shown, the lower ends of the flues of both series 13, 14 of heating walls are communicably connected by channel and duct means with air and fuel gas regenerators for supplying to the said flues air and fuel gas 50 when the direction of combustion is upwardly through the flues.

Extending longitudinally of the battery is a pair of waste gas tunnels or stack flues 61 and 62, the waste gas tunnel 61 serving 55 for the sub-group R of regenerators of each main group T and the waste gas tunnel 62 serving for the sub-group S of regenerators of the aforesaid main group T. Both said waste gas tunnels lead to the usual waste 60 gas stack. Flow boxes 63 connect the sole channels of the several regenerators individually with their respective waste gas tunnels 61 or 62. The flow boxes 63 are provided with valves 64 for controlling the flow 65 between the individual regenerators and

their respective waste gas tunnels. The valves 64 of all of the regenerators of the group S are open, while concurrently the valves 64 of all of the regenerators of the group R are closed. On reversal of the battery, the valves 64 of the group R of regenerators are open and the corresponding valves of the group S are closed. Each regenerator A of both groups R and S is provided with a lid 65 which when open permits air to flow into the regenerator. The series of air lids 65 of the regenerators of the groups R and S are opened in alternation, whereby all the regenerators A of the group R operate concurrently for inflow of air during one reversal period and thereafter, during the next reversal period, the regenerators A of the group S operate for inflow of air, while the regenerators A of the group R are operating for outflow of the waste gases.

A fuel gas main 66 extends longitudinally of the battery and is provided with individual valve connections 67 to the several regenerators P of both groups R and S. In the operation of the battery, the valve connections of the regenerators P of the group R are operated in unison to permit the flow of fuel gas into said regenerators from the main 66, while the valve connections 67 of the regenerators P of the group S are closed to shut off the supply of fuel gas. On reversal of the battery, the valve connections 67 are operated to permit the supply of gas into the regenerators P of the group S and concurrently to cut off the supply of gas from the regenerators P of the group R.

The operation of the retort battery, assuming that a relatively lean or dilute gas, such as ordinary producer gas is employed as the fuel in the heating walls is as follows: If it be assumed that the several regenerators composing the group R be operating for inflow, and the flues throughout the battery be operating for downflow, it follows that during this period of operation the regenerators P of the group R are employed for preheating the fuel gas which is subsequently introduced into the flues. The regenerators A of the group R are employed for preheating the air to support the combustion of the gas in the flues. Concurrently, all the regenerators of the group S operate for outflow, or as waste gas regenerators W. The air and fuel gas passes upwardly through the regenerators A and P of the group R, thence into the longitudinal channels 42 and 45, from which the air and fuel gas passes through the ports 43 and 46 into the flues 37 of both series 13, 14 of heating walls. The waste gases from the bottoms of the flues exhaust through the bottom horizontal channels 54 and 59 into the vertical channels 53 and 58 which deliver the waste gases into the tops of the several regenerators of the group S.

Passing downwardly through the regenerators S, the waste gases flow through the open flow boxes 63 of such regenerators into the waste gas tunnel 62. On reversal of the 5 battery, the regenerators A and P of the group S deliver to the bottoms of the flues the air and fuel gas through the vertical channels 53 and 58 and horizontal channels 54 and 59. The waste gases from said 10 flues exhaust from the top thereof into the channels 42 and 45 and thence pass directly into the tops of the regenerators of the group R. Flowing downwardly through said regenerators, the waste gases ultimately 15 pass through their open flow boxes 63 into the waste gas tunnel 61.

The by-products and distillate gases from the several retorts or coking chambers of both series 11, 12 pass out of the tops of 20 said retorts through ascension pipes 68, 69 individual to the respective retorts of the series 11, 12. These ascension pipes carry the distillate and by-products to a common collecting main 70, through which the distillate and by-products may pass to the usual by-product recovery apparatus.

In the construction of the battery, the crosswise expansion joints, such as the joints 71, may be located between the individual units T of regenerators, heating walls and retorts and in vertical planes and remotely from the heating walls. In addition to these joints 71, each chamber 11, 12 has a crosswise expansion joint 72 permitting longitudinal expansion of the individual chambers. Longitudinally-extending expansion joints 73 are located at the ends of the several regenerators and between them and the chamber and port regions, 35 with the result that the regenerators of each unit of the battery between crosswise expansion joints 71 may expand or contract independently of their corresponding chamber and port regions, and expansion of the 40 chamber and port regions which are heated to different temperatures from the regenerators will not effect the expansion or contraction of the structure of the regenerators. With the main expansion joints so 45 disposed in vertical planes and between independently operable units of the battery leakages or short circulating of the flow of the various gaseous media are avoided.

The invention as hereinabove set forth 50 may be variously embodied within the scope of the claims hereinafter made.

I claim:

1. In a vertical retort battery, in combination: a plurality of high narrow retort 55 chambers, each adapted to receive through its top the charge to be coked and adapted to discharge through its bottom the coked charge; heating walls contiguous to such retort chambers and respectively comprising 60 combustion flues alternately operable in

unison for either upflow or downflow combustion; two groups of high narrow regenerators disposed at the same level, one operating for inflow during upflow combustion of the flues and the other group operating 70 for inflow during the alternate downflow combustion of the flues, each group of the said regenerators comprising air and fuel gas regenerators; flow connections communicably connecting the first mentioned group of 75 regenerators with said flues at the bottoms of the flued walls; and flow connections communicably connecting the second mentioned group of regenerators with said flues at the tops of the flued walls; the regenerators, 80 heating walls and coking chambers being disposed into operating units with the flow connections between the regenerators and flues of one unit operating independently of the flow connections of the other units, 85 whereby each unit of the battery may be operated and controlled independently of the other units; substantially as specified.

2. In a vertical retort battery, in combination: a plurality of high narrow retort 90 chambers; heating walls contiguous to such retort chambers and respectively comprising combustion flues alternately operable in unison for either upflow or downflow combustion; two groups of high narrow regenerators disposed at the same level, one operating 95 for inflow during upflow combustion of the flues and the other group operating for inflow during the alternate downflow combustion of the flues, each group of said regenerators comprising air and fuel gas regenerators; flow connections communicably connecting the first mentioned group of regenerators with said flues at the bottoms of the flued walls; and flow connections communicating 100 connecting the second mentioned group of regenerators with said flues at the tops of the flues; the regenerators, heating walls and coking chambers being disposed into operating units with the flow connections between the regenerators and flued walls of one unit operating independently of the flow connections of the other units, 105 whereby each unit of the battery may be operated and controlled independently of the other units; substantially as specified.

3. In a vertical retort battery, in combination: a plurality of high narrow retort 110 chambers; heating walls contiguous to such retort chambers and respectively comprising combustion flues; two groups of high narrow regenerators disposed at the same level, one operating for inflow during upflow combustion of the flues and the other group operating 115 for inflow during the alternate downflow combustion of the flues, each group of the said regenerators comprising air and fuel gas regenerators; flow connections communicably connecting the first mentioned group of regenerators with said flues at the bottoms 120 in

of the flued walls; and flow connections communicably connecting the second mentioned group of regenerators with said flues at the tops of the flued walls; the regenerators, 5 heating walls and coking chambers being disposed into operating units with the flow connections between the regenerators and flues of one unit operating independently of the flow connections of the other units, 10 whereby each unit of the battery may be operated and controlled independently of the other units; substantially as specified.

4. In a vertical retort battery, in combination: a plurality of high narrow retort chambers; heating walls alternating with such retort chambers in a longitudinal row and respectively comprising combustion flues; two groups of high narrow regenerators disposed at the same level as the heating 20 flues and on the same side thereof, one operating for inflow when the other operates for outflow; flow connections communicably connecting each group of regenerators with said flue; the regenerators, heating walls 25 and coking chambers being disposed into operating units with the flow connections communicably connecting the regenerators with the flues of one unit operating independently of the flow connections of the other units, 30 whereby each unit of the battery may be operated and controlled independently of the other units; substantially as specified.

5. In a vertical retort battery, in combination: a plurality of high narrow retort 35 chambers, each adapted to receive through its top the charge to be coked and adapted to discharge through its bottom the coked charge; heating walls contiguous to such retort chambers and respectively comprising 40 combustion flues alternately operable in unison for either upflow or downflow combustion; two groups of high narrow regenerators disposed at the same level, one operating for inflow during upflow combustion of the 45 flues and the other group operating for inflow during the alternate downflow combustion of the flues; flow connections communicably connecting the first mentioned group of regenerators with said flues at the bottoms 50 of the flued walls; and flow connections communicably connecting the second mentioned group of regenerators with said flues at the tops of the flued walls; the regenerators, heating walls and coking chambers being disposed into operating units with the flow connections 55 between the regenerators and flues of one unit operating independently of the flow connections of the other units, whereby each unit of the battery may be operated and 60 controlled independently of the other units; substantially as specified.

6. In a vertical retort battery, in combination: a plurality of retort chambers; heating 65 walls contiguous to such retort chambers and respectively comprising combustion

flues alternately operable in unison with either upflow or downflow combustion; two groups of regenerators, one operating for inflow during upflow combustion of the flues and the other group operating for inflow during the alternate downflow combustion of the flues; and flow connections communicably connecting the first mentioned group of regenerators with said flues at the bottoms of the flued walls and flow connections 75 communicably connecting the second mentioned group of regenerators with said flues at the tops of the flued walls; the flow connections between each regenerator and its communicably connected flues being independent of the flow connections between any other regenerator and flues; substantially as specified.

7. In a vertical retort battery, in combination: two series of high narrow retort chambers respectively disposed along opposite sides of the battery; heating walls contiguous to such retort chambers and respectively comprising combustion flues alternately operable in unison for either upflow or downflow combustion; two groups of high narrow regenerators disposed in the interior of the battery between the two series of retort chambers, one operating for inflow during upflow combustion of the flues 90 and the other group operating for inflow during alternate downflow combustion of the flues; and flow connections communicably connecting the first mentioned group of regenerators with said flues at the bottoms of the flued walls, and flow connections communicably connecting the second mentioned group of regenerators with said flues at the tops of the flued walls; the flow connections communicably connecting each regenerator and its communicably connected flues being independent of the flow connections between any other regenerator and flues; substantially as specified.

8. A battery structure for distilling carbonaceous materials comprising high narrow distilling chambers and flued heating walls contiguous to such distilling chambers; the walls and chambers being disposed in series along the opposite sides of the battery structure, combined with high narrow regenerators disposed in the interior of the structure and between the opposite series of said distilling chambers and heating walls and communicably connected with the flues of the latter; the regenerators, distilling chambers and heating walls being disposed in operating units each unit operable and regulable independently of the other units; substantially as specified.

9. A battery structure for distilling carbonaceous materials having distilling chambers and flued heating walls contiguous to said distilling chambers, the walls and chambers being disposed in series along the oppo-

- site sides of the battery structure, combined with regenerators disposed in the interior of the structure and between the opposite series of said distilling chambers and heating walls, each regenerator being communicably connected with flues of said heating walls independently of the other regenerators; substantially as specified.
10. A vertical retort battery having retort chambers, heating walls alternating with the retort chambers in a longitudinal row, said heating walls comprising vertical combustion flues, combined with regenerators disposed in a series extending along one side, only, of the series of the aforesaid retort chambers and heating walls, each regenerator having flow connections communicably connecting the regenerator with flues of the heating walls independently of the flow connections communicably connecting the other regenerators with flues of the heating walls; substantially as specified.
11. A regenerative battery structure for effecting heat treatment of materials embodying: a series of regenerators, chambers and contiguous heating walls disposed in series along the series of regenerators with longitudinal expansion joints between the regenerative region and the chamber and heating wall region for permitting the regenerative region to expand or contract independently of the chamber and heating wall region; substantially as specified.
12. A regenerative battery structure for effecting heat treatment of materials embodying: a series of regenerators, chambers and alternate heating walls disposed in series along the series of regenerators; the regenerators, chambers and alternate heating walls being separated by crosswise walls into separately operable units with crosswise expansion joints permitting independent expansion or contraction of each battery unit, there also being longitudinal expansion joints between the regenerative region and the chamber and heating wall region of each unit for permitting the regenerative region to expand or contract independently of the chamber and heating wall region; substantially as specified.
13. In a vertical retort battery, in combination: a plurality of substantially parallel high narrow retort chambers, each adapted to receive through its top a charge to be coked and adapted to discharge through its bottom the coked charge; heating walls between and contiguous to said retort chambers and respectively comprising combustion flues; high narrow regenerators serving the flues of the heating walls respectively and arranged alongside of the series of retorts and heating walls, said regenerators being disposed in position side by side and spaced from each other by regenerator walls parallel with said retort chambers and heating walls; and expansion joints in the walls, of said retort chambers, that are adjacent said regenerators, said joints extending from the retort chambers to the said regenerator walls.
14. In a vertical retort structure: a coking chamber; a heating wall contiguous thereto and having flues; a regenerator at one side of and, contiguous to, the coking chamber communicably connected to the flues of the flued wall; and an expansion joint between said coking chamber and the regenerator chamber.
15. In a vertical retort structure; a coking chamber; a heating wall contiguous thereto and having flues; a regenerator chamber at one side of, and contiguous to, the coking chamber communicably connected to the flues of the flued wall; and an expansion joint extending from the coking chamber through the side wall thereof that is adjacent said regenerator chamber.
16. In a vertical retort structure; a coking chamber; a heating wall contiguous thereto and on the same level therewith and having flues; a walled regenerator contiguous to said coking chamber and on substantially the same level as said coking chamber and the flued heating wall and communicably connected to the flues of the flued wall; and an expansion joint between said coking chamber and said regenerator, said joint extending from the coking chamber to a wall of said regenerator.
17. The combination as defined in claim 14, in which a vertical channel is provided in said expansion joint between the coking chamber and regenerator chamber.
18. The combination as defined in claim 16, in which a vertical channel is provided in said expansion joint.
19. In a coke oven structure, the combination of a row of sections; each of said sections comprising a structural unit consisting of a flued heating wall, and walls at each end of said heating wall; said sections being disposed adjacent to and laterally of each other with the heating walls parallel and together forming vertical retort coking chambers; each section being connected for expansion with an adjacent section by an expansion joint extending through the walls at each end of the heating walls from the coking chamber to the outside of said section.
20. In a coke oven structure, the combination of a row of sections; each of said sections comprising a structural unit consisting of a flued heating wall, and walls at each end of said heating wall; said sections being disposed adjacent to and laterally of each other with the heating walls parallel and together forming vertical retort coking chambers; each section being connected for expansion with an adjacent section by an expansion joint, the successive joints being

spaced from each other substantially the same distance as successive coking chambers.

21. In a vertical retort oven, in combination: a plurality of substantially parallel vertical coking chambers; heating walls between and contiguous to said coking chambers and respectively comprising combustion flues; a series of regenerators arranged alongside of the series of coking chambers and heating walls and communicably connected with the flues of said heating walls, said regenerators being disposed in position side by side and spaced from each other by regenerator walls parallel with said coking

10 chambers and heating walls; a wall extending transversely of said coking chambers,

heating walls, regenerators and said regenerator walls and interposed between the coking chambers and their heating walls on the one hand and the regenerators and said regenerator walls on the other hand; and an expansion joint extending laterally through the transversely extending interposed wall, from each of said coking chambers to one of said regenerator walls, each of the expansion joints extending upwardly through the transversely extending interposed wall from the bottoms to the tops of the said vertical coking chambers.

25 30 In testimony whereof I have hereunto set my hand.

JOSEPH VAN ACKEREN
